UNITED STATES PATENT OFFICE

STANLEY M. JONES, OF RICE LAKE, WISCONSIN

WINDOW SCREEN FOR AUTOMOBILES

Application filed April 11, 1930. Serial No. 443,503.

The present invention appertains to screens particularly adapted for use in connection with the windows of the closed type of automobiles such as are now commonly in use.

5 An important object of the present invention resides in the provision of a screen formed in two sections slidably connected together and means whereby the sections may be frictionally held in a desired adjusted position.

10 Another very important object of the invention resides in the provision of an adjustable screen of this nature which is exceedingly simple in its construction, easy to manipulate, thoroughly efficient and reliable in use and otherwise well adapted to the purpose for which it is designed.

15 With the above and numerous other objects in view as will appear as the description proceeds, the invention resides in certain novel features of construction, and in the combination and arrangement of parts as will be hereinafter more fully described and claimed.

20 In the drawing:

25 Figure 1 is an elevation of the screen in the window opening of a door of an automobile.

Figure 2 is an elevation of the screen,

30 Figure 3 is a fragmentary vertical longitudinal section through the frame thereof,

Figure 4 is a horizontal detail section taken substantially on the line 4—4 of Figure 3, and

35 Figure 5 is a detail vertical section taken substantially on the line 5—5 of Figure 3.

Referring to the drawing in detail it will be seen that the screen comprises sections A and B. Section A comprises longitudinal channel frame members 5 and end channel frame members 6 and a sheet of foraminous material noted by the numeral 7 is stretched across the frame to one side thereof as is clearly illustrated in Figure 5.

The section B comprises longitudinal channel members 8 and end channel members 9 and a sheet of foraminous material is stretched across the frame being anchored in the channel frame members as clearly illustrated in Figure 5. One of the channel end members 9 has its back open as is clearly

illustrated in Figure 4 and a pair of channel links 11 are pivotally connected together as at 12 and pivotally connected to the corners of the frame of the section B as at 14 and are of sufficient length so that when the links are moved to a substantially alined position as shown in Figure 3 they spread the frame of the section B into frictional locking engagement with the frame of the section A, it being understood that longitudinal members 8 are slidably mounted in longitudinal members 5.

From the above detailed description it will be seen that the two sections A and B are put together with the locking device formed by links 11 in their broken position. The closed car window is lowered. The screen is then inserted in the same felt or rubber groove that the glass slides in, in the extreme top of the door or window frame. The two sections are then pulled out until they reach from side to side of the door frame.

Then the locking device is pushed into its locking position as shown in Figure 3 which spreads the sides of the section B to lock the screen in position above the glass.

The glass is then rolled up to the bottom of the screen.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It is apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A window screen comprising a screen section including longitudinal channel bars,

a second screen section including longitudinal channel bars slidably fitted in the channel bars of the first section, and a toggle connected at its ends with the channel bars of the second section for moving the same into and out of frictional engagement with the channel bars of the first section.

2. A window screen comprising a pair of screen sections, one of which is slidable within the other, and a toggle connected at its ends with the section which is slidable in the other.

In testimony whereof I affix my signature.
STANLEY M. JONES.
